CALENDAR

Edmund J. Phillips, Louisville, Ky.

Application June 13, 1946, Serial No. 676,518

5 Claims. (Cl. 40—115)

1

This invention relates to a calendar, and more particularly to a long term calendar of the so-called perpetual type.

Many types of long term or perpetual calendars have been proposed. In all such types, the problem of correctly indicating the 29th, 30th and 31st days of a month as well as the problem of leap years have been major ones. Most attempts to solve these problems have resulted in devices so complicated and involved as to render them impractical.

In overcoming the aforesaid problems, it is a major object of my invention to provide a novel calendar that is simple in construction, easy to manipulate, and wherein the 29th, 30th and 31st day and the leap year problems are solved in simple manner.

A further object of my invention is the provision of a novel long-term calendar wherein the result of the manipulations is set up in a manner corresponding substantially to the form of a conventional calendar, thereby making the calendar easy to read and more attractive from a practical viewpoint.

A further object of my invention is the provision of a novel long-term calendar wherein key symbols in the nature of advertising matter can be employed in setting the calendar, thereby calling the attention of the user to the advertising on the calendar each time the latter is reset.

Other objects and advantages of my invention will appear from the following description and claims taken in connection with the attached drawings wherein:

Fig. 1 is a front view of one embodiment of my invention, showing the resultant calendar as secured by adjustment of the two members forming the assembly.

Fig. 2 is a side elevation of the embodiment of Fig. 1 showing the two members in assembled position.

Fig. 3 is the rear face of the front member of Fig. 1.

Fig. 4 is a view of the front face of the rear member on an enlarged scale.

Fig. 5 is a view of the rear face of the rear member, also on an enlarged scale.

Fig. 6 is a front view of a modified form of my invention wherein the calendar proper is positioned on an arc.

Fig. 7 is a side elevation of the assembly of Fig. 6.

Fig. 8 represents the front face of the rear member of the assembly of Fig. 6.

2

Fig. 9 represents the rear face of the rear member of Fig. 6.

Referring to the calendars shown in the drawings, which are to be understood as only illustrative of my invention and not limiting, Figs. 1-5, inclusive, show a calendar composed of a front member 11 and a rear member 12 secured together at their centers by a pivot pin 13 such as a rivet, or equivalent fastening means so that one member can be rotated relative to the other. The front of the assembly is shown in Fig. 1. In this view, a conventional calendar table 14 covering a 28-day month, and imprinted on the front face of front member 11, is visible together with a second table 15 likewise imprinted on the front face of member 11 and containing three blocks denoting the 29th, 30th and 31st days of a month. It will be noted that table 15 is located or positioned as an extension of table 14. Front member 11 is apertured as shown to form seven day slots 16, appropriately positioned at an end of each vertical column of table 14, and is also apertured to provide three day slots 17, similarly positioned relative to table 15. Slots 17 are positioned radially outwardly relative to the extremity of slots 16. The remainder of the front face of member 11, which may be circular or square, preferably the latter, is available for advertising matter or any desired design.

Member 12, appearing beneath as shown in Fig. 4, member 11 in Fig. 1, has arranged in concentric circles corresponding to the radial positions of slots 16 from the pivot 13, indicia indicating the days of the week imprinted thereon, each circle being divided into forty arcuate spaces with one blank space appropriately positioned in each circle. There is also provided indicia corresponding to certain days of the week printed in three exterior concentric circles, which are divided into forty arcuate spaces. However, in this series in the innermost circle there is one blank space, and in the two outer circles there are various blank spaces. When member 12 is properly positioned, as will hereinafter appear, the correct day indications for a selected month are visible through slots 16 and 17 and correctly positioned relative to the numbers of tables 14 and 15. If the month be February in other than a leap year, the twenty-ninth day thereof, indicated at 20 in the eight concentric circles, are imprinted with a contrasting color such as red, so that when they are exposed through slots 17 they are to be disregarded. An instruction to this effect is suitably printed on the calendar under table 15. If the month be February in a leap

year, the correct day indication will appear in the contrasting color in slot 17 under "29," the slots "30" and "31" being blank. If the month selected be a 30 day month, the correct day designation will appear beneath "29" and "30" but will be blank under "31." If the month selected be a 31 day month, correct day designations will appear in all slots beneath table 15. This arrangement is thus suitable for months of any length, and it presents the information in an arrangement comparable to that of the conventional calendar.

The rear face of member 12 (Fig. 5) is provided with radially extending columns of tables 18 which are 18° apart, center to center, and a similar series 19, of a contrasting color is arranged in columns 18° apart displaced toward the first series by nine degrees. For instance, table 18 may be printed in black and table 19 in red, the latter being shown in dotted lines in Fig. 5 for the purpose of contrast, and the outer ends of the tables terminate in indicators such as an arrow head 21. Each table contains the complete series of years for the term of the calendar, the columns being arranged in each series according to alternate days of the week, table 18 having the years arranged according to identical third months with a blank space inserted after each fourth space in each column, and table 19 having the years arranged according to identical first months with a blank space inserted after each fourth space in each column.

The rear face of member 11 (Fig. 3) has a table 22 imprinted thereon as shown bearing consecutively the names of the months of the first half of the year, and spaced 9° center to center, the lower end of each month block being indexed at the center to register with an arrow head 21 of tables 18 or 19. The months blocks for January and February are of a color corresponding to tables 19 and are shown in dotted lines by way of contrast. The months of the second half of the year are arranged consecutively in a series 23 forming a continuation of series 22 but displaced away from the first series by twenty-seven degrees or three monthly spaces. The week day tables on one face of member 12 are arranged in predetermined relation with respect to the year columns on the opposite face and the month indices on the obverse face of member 11, the matching points being indicated by the arrow heads or indices at the outer and inner edges of the peripheries of tables 21 and 22, 23, respectively.

In setting the calendar for the month and year desired, the year tables and month blocks 22 in dotted lines or contrasting design or color are used for the months of January and February and the remaining year and month tables for the other months. The table in which the year is located is positioned by rotating member 12 until the arrow head on the table registers with the block on member 11 corresponding to the selected month. The proper calendar then appears on the front of the device.

For example, if it is desired to set up a calendar for January of 1946, reference is made only to the table in dotted lines. The year 1946 is found in the last table 19. Member 12 is then rotated to align this table with the January block in table 22 of member 11. This operation sets the correct calendar on the front of the assembly.

If it is desired to set up a calendar for May, 1946, the black or solid line year table and month block are used. The year 1946 is found in the

last solid table. Member 12 is then rotated to align this table with the May block of table 22 whereupon the correct calendar is set on the front of member 11.

5 It will be noted that the operation is very simple, only one setting being required for each month. It will also be noted that the years in tables 18 and 19 are also in approximate order, thereby facilitating their location.

Figs. 6 to 9, inclusive, illustrate a modification of my invention wherein the resultant calendar as viewed in Fig. 6 differs slightly from the conventional style in that the table is slightly arcuate in shape. The assembly of Fig. 6, like the assembly of Fig. 1, is formed of a front member 31 and a rear member 32, the two members being secured together at their centers by a suitable pivot pin such as a rivet 33 (Fig. 8).

A substantially conventional 28-day calendar table 34 is imprinted on the front of member 31, a second table 35 being also imprinted thereon preferably within the radial span of table 34 to provide for the 29th, 30th and 31st days. It will be noted that table 35 is positioned as an extension of table 34. An arcuate slot 36 is provided in member 31 above table 34 through which the appropriate day designations, appearing on the front face of rear member 32, can be viewed, as will hereinafter be explained. A similar slot 37 is provided beneath table 35 for a like purpose, indicia appearing thereon only when the selected month has more than 28 days as explained in connection with the modification of Fig. 1. If desired, a second arcuate slot 38 may be provided beneath table 34 so that additional designations of the days of the week as imprinted on the front face of member 32 may be viewed therethrough.

An arcuate slot 39 is provided at the bottom of member 31 through which the months of the year as imprinted on the front face of member 32 can be viewed and keyed with a symbol such as a word or an advertising slogan 41 in a manner to be described to set the calendar.

40 As shown in Fig. 8, member 32 has a table 42 with the days of the week imprinted thereon in five consecutive series to register with slot 36 of member 31, and has a table 43 of the months of the year radially located to register with slot 39 of member 31. A table 44 of the 29th, 30th and 31st days of the month is radially located to register with slot 37 of member 31, and a table 45 of the days of the week to register with slot 38 of member 31. It will be noted that tables 42 and 45 are circumferentially aligned and carry the same data. The day designations of table 44 indicated at 40 are in a contrasting color relative to the colors of the other elements, these elements being effective only in leap years as noted in the legend under opening 37.

45 The rear face of member 32 carries tables 46 and 47, preferably in contrasting colors or designs, table 46 being shown in solid lines and table 47 in dotted lines. In each table the columns cover an arcuate expanse of $1/35$ of a circle and the tables are spaced $1/5$ of a circle apart. Each table is headed by a key word of the seven word slogan appearing on the front face of member 31. Table 47 is to be used only for the months of January and February, and table 46 for the remaining months. The years in the tables are arranged in numerical sequence with each fifth space skipped and left blank. Each column of years is keyed by the word of the slogan, the 50 whole slogan covering an expanse of $1/5$ of a circle;

and each word covering an arcuate expanse of $\frac{1}{35}$ of a circle.

If the month selected be January of 1950, the year 1950 is located in table 41. It appears there under the key word "Always." January of table 43 is then aligned with the word "Always" of table 41 whereupon the correct calendar will be set up. If the month selected be November of 1942, table 46 is used and the key word is found to be "Beer." November of table 43 is then matched with "Beer" of table 41 and the correct calendar set up.

It will be noted that all the operations are simple and that the tables are also simple and easy to handle. Only one mechanical movement is required with each calendar. While I have shown calendars covering only the years 1900 to 2000, it is to be understood that the range of the calendars may be increased by enlarging the year tables.

Having described my invention, I claim:

1. A long term calendar comprising: a front member and a rear member operatively connected to be moved relative to one another, the front member being provided with a 28-day month table and a separate table for days of the month in excess of 28 days, the member being apertured to form openings for the days of the week appropriately located relative to the elements of the tables, one face of the rear member being provided with series of indicia concentrically arranged and indicating the days of the week for both said tables arranged to register with the apertures in the front member to complete the calendar, a face of one of said members having indicia arranged in a set of seven columns of years having identical months of January and February, and a set of seven columns of years having identical months of March to December, indicia indicating consecutively the months of the year provided on the other of said members and arranged to be selectively registered with a year to form a complete calendar for the selected month and year visible on the front face of the assembly.

2. A long term calendar comprising: a front member and a rear member operatively connected to be moved relative to one another, the front member being provided with a 28-day month table and a separate table for days of the month in excess of 28 days, the member being apertured to form openings for the days of the week appropriately located relative to the elements of the tables, the front face of the rear member being provided with series of indicia concentrically arranged and indicating the days of the week for both said tables arranged to register with the apertures in the front member to complete the calendar, the rear face of the rear member having indicia arranged in a set of seven columns of years having identical months of January and February and indicia arranged in a set of seven columns of years for the remaining months of the year, indicia indicating consecutively the months of the year being provided on the front member and arranged to be selectively registered with a year to form a complete calendar for the selected month and year visible on the front face of the assembly.

3. A long term calendar comprising: a front member and a rear member operatively connected to be moved relative to one another, the front member being provided with a 28-day month table and a separate table for the 29th, 30th and 31st days of a month, the member be-

ing apertured to form openings for the days of the week appropriately located relative to the columns of the tables and an arcuate-shaped opening divided into a series of adjacent sections, each section being indicated by a key symbol, the front face of the rear member being provided with indicia indicating the days of the week for both said tables arranged to register with the apertures in the front member and the months of the year for registry with the arcuate-shaped opening to complete the calendar, the rear face of the rear member bearing indicia arranged in a set of seven columns of years covering the term, the years running consecutively across the columns and providing a blank space after each fourth space in each column, and a second set of seven columns of years covering the term, the years running consecutively across the columns and providing a blank space after each fourth space in each column whereby the years of the first series are progressively displaced from the positions in the second series, each column of each series being indicated by key symbols, the key symbol for the selected year being determined from said year indicia and the desired month registered with the corresponding symbol on the front face of the front member to form a complete calendar for the selected month and year visible on the front face of the assembly.

4. A long term calendar comprising a front member and a rear member pivoted together, one said member providing seven radial columns arranged equidistantly apart corresponding to alternate days of the week and having the years for the term arranged therein according to identical first months, a second seven radial column series arranged equidistantly apart corresponding to alternate days of the week and having the years arranged therein according to identical third months, said second radial table being displaced a half arcuate space toward said first table so as to alternate therewith; an arcuate first monthly half year table carried by the other member and arranged consecutively in equal arcuate monthly spaces which are one half of those between the year columns, and a second monthly half year table forming a continuation of the first half year table and displaced away therefrom three month spaces, a numbered twenty-eight day month table on one of said members having seven vertical columns corresponding to the days of the week, there being an aperture arranged at the end of each vertical column; a supplemental table positioned radially displaced from the first table and having a horizontal row of numbers from twenty-nine to thirty-one inclusive, there being an aperture arranged for each number; one of said members having thereon the days of the week arranged in seven concentric circles corresponding respectively to the radial distances of said apertures from the center, and having another series of three concentric circles bearing days of the week corresponding respectively to the radial distances of the columns of the supplemental table; said concentric circles providing equal day spaces the same arcuate distance as said month spaces, whereby registration of the year and month produces a calendar for the month.

5. A long term calendar comprising a front member and a rear member pivoted together, one said member providing seven radial columns arranged equidistantly apart and having the years for the term arranged therein; a second seven radial column series arranged equidistantly apart

and having the years for the term arranged therein; an arcuate monthly table, a numbered twenty-eight day month table having seven vertical columns corresponding to the days of the week, there being an aperture arranged at the end of each vertical column; a supplemental table positioned radially displaced from the first table and having a horizontal row of numbers from twenty-nine to thirty-one inclusive, there being an aperture arranged for each number; one of said members having thereon the days of the week arranged in concentric circles corresponding respectively to the radial distances of said apertures from the center, and having another series of concentric circles bearing days of the week corresponding respectively to the radial distances of the apertures of the supplemental table; said concentric circles providing equal day spaces the same arcuate distance as said month spaces.
